US0D1082819S

(12) **United States Design Patent** (10) Patent No.: **US D1,082,819 S**
(45) Date of Patent: ** Jul. 8, 2025

(54) **DISPLAY SCREEN WITH GRAPHICAL USER INTERFACE**

(71) Applicant: **JVCKENWOOD Corporation**,
Yokohama (JP)

(72) Inventors: **Aiko Takiwaki**, Yokohama (JP); **Risa Sonobe**, Yokohama (JP); **Makoto Gondo**, Yokohama (JP)

(73) Assignee: **JVCKENWOOD Corporation**,
Yokohama (JP)

(**) Term: **15 Years**

(21) Appl. No.: **29/905,006**

(22) Filed: **Oct. 16, 2023**

(30) **Foreign Application Priority Data**

Apr. 18, 2023 (JP) ..... 2023-008048 D
(51) LOC (15) Cl. 14-04
(52) U.S. Cl. ..... USPC D14/486
(58) Field of Classification Search
USPC D14/485-495
CPC G06F 3/048-04897
See application file for complete search history.

(57) **CLAIM**

The ornamental design for a display screen with graphical user interface as shown and described.

DESCRIPTION

The sole FIGURE is a front view of a display screen with graphical user interface, showing our new design.

The outer broken lines in the Figure represent a display screen or a portion thereof, and form no part of the claimed design. The other broken lines within the FIGURE show portions of the display screen with graphical user interface that form no part of the claimed design.

1 Claim, 1 Drawing Sheet
